UNITED STATES PATENT OFFICE

CLAUDE A. BULKELEY, OF KENMORE, NEW YORK

DEVICE FOR ELIMINATING THE TRANSMISSION OF EXTRANEous NOISES IN
TELEPHONE CIRCUITS

Application filed June 11, 1929. Serial No. 369,948.

This invention relates to a device for eliminating the transmission of extraneous noise over telephone circuits, and more particularly to a device which is adapted to be attached to any standard telephone transmitter and which when applied eliminates the buzzing or rushing sound heard in a telephone receiver due to the noise in the room or locality in which the telephone transmitting instrument 10 and the receiver is located.

The principal object of this invention is therefore to provide a simple, inexpensive device of this character which can be attached to any standard telephone transmitter and which when so attached effectively eliminates the effect of extraneous noises on the transmitting diaphragm so as to cut out the usual buzzing or rushing sound caused by vibrations set up within the telephone transmitter housing by extraneous sound vibrations from the room where the transmitter is located striking the transmitter housing. This buzzing or rushing sound which is eliminated by the present invention is heard in the receiver of the transmitter affected by the extraneous noise, i. e., in the receiver located in the room where the extraneous noise causing the buzzing or rushing sound exists.

In the accompanying drawings:

30 Figure 1 is a fragmentary front view of a telephone transmitter showing my invention applied thereto.

Figure 2 is a side view thereof.

35 Figure 3 is a perspective view of my invention detached from a telephone, showing the position of its parts when applied to a telephone.

40 Figure 4 is a side elevation of my invention showing the position of the parts before it is applied to a telephone.

Similar reference numerals refer to similar characters in the several figures of the drawings:

45 The telephone shown in the drawings is of standard form and includes a standard 5 carrying a pivot pin 6 on which the transmitter casing section 7 is pivotally mounted so that the transmitter housing can be moved to any desired angle relative to the stand. The transmitter casing section 7 is bell shaped

and is open at its front end, the casing section being closed by a front cover plate 8 which is secured in any suitable manner as by screws 9 received in slots at the edge of the transmitter casing section. At the center of the front cover plate 8 the usual threaded opening is provided in which is screwed the usual hard rubber mouthpiece 10. The electrical mechanism for transmitting sounds directed into the mouthpiece 10 is carried by 55 the front plate 8 and is housed within the transmitter casing section 7. This mechanism includes the usual diaphragm (not shown) which is disposed immediately behind the front plate 8 so that the sound vibrations from the mouthpiece vibrate this diaphragm.

It has been found that extraneous sound vibrations in the room where the transmitting instrument and its receiver are located, 70 strike the front casing plate 8 of the transmitter housing and this vibration of the transmitter cover plate 8 sets up a vibration of the air in the transmitter housing which results in an undesired vibration of the diaphragm and a buzzing or rushing noise being transmitted to the receiver forming a 75 part of the instrument of the transmitter affected by the extraneous noise and located in the same room. It has been found that a 80 device which exerts a yielding pressure on the outer face of the transmitter cover plate 8 and against the rear face of the transmitter casing section 7 will prevent its vibration under extraneous sound vibrations and 85 hence eliminate the buzzing or rushing sound heard in the receiver of the telephone set being used in the room where the extraneous noise exists. A device for accomplishing this is constructed in accordance with 90 the present invention as follows:

The numeral 11 represents a piece of wire which is bent to provide a depending front U-shaped part 12, the upper ends or legs of which terminate in two spring loops 13. 95 The front U-shaped part 12 is sufficiently wide to receive the neck of the mouthpiece 10 and the spring loops 13 are positioned so as to be arranged over the transmitter casing section 7, and the lower end of the front 100

U-shaped part arranged under the mouth-piece 10. The other ends of each of the spring loops 13 extend downwardly to form two legs 14. These legs are preferably held in proper spaced relation by a wire link 15, which is preferably made in the form of a metal band so that the name of the manufacturer or other markings can be impressed on the same. At the lower end of the front 10 U-shaped part 12 a rubber button or presser member 16 is secured and a similar rubber button or presser member 17 is secured to the lower end of each of the legs 14. These rubber buttons or presser members may be 15 attached to the wire in any suitable manner, but the wire is preferably deformed at the places of attachment and the rubber buttons are moulded to the deformed parts.

To attach the device to the telephone 20 transmitter, the mouthpiece 10 is preferably first removed and the attachment, as illustrated in Figure 3, is slipped over the transmitter housing so that the front rubber button or presser member bears against the 25 front cover plate 8 at a place immediately below the mouthpiece hole and within the margin of the front cover plate 8, and the legs 14 are disposed on opposite sides of the neck of the transmitter housing and the rubber 30 presser members 17 carried thereby bear against the lower rear face of the transmitter casing section 7 on opposite sides of the rubber button 16. The front rubber buttons or presser members 16 are also preferably 35 so disposed that they bear against the under side of the mouthpiece 10 when the mouthpiece is replaced. When the mouthpiece is so replaced the telephone is ready for operation and the device functions to eliminate 40 the buzzing or rushing sound occasioned by extraneous noise in the room where the telephone instrument is located.

By reason of the spring loops 13, 13, the 45 rubber presser buttons 16 and 17 are yieldingly held near each other and when the device is applied to a telephone as described, these springs operate to hold the rubber button 16 against the front transmitter cover 8 and the button 17 against the rear side of 50 the transmitter casing section 7 and hence prevent the transmitter cover plate and the casing section from vibrating in response to extraneous noises. This cuts out the corresponding vibration of the diaphragm and hence eliminates the buzzing or rushing 55 noise frequently encountered in the receivers of telephone instruments located in noisy rooms which buzzing or rushing noise is caused by the vibration of the transmitter 60 housing by the extraneous sounds in the noisy room and this device therefore makes the conversation more clear and the transmission more pleasing.

This invention therefore provides a device 65 for eliminating disagreeable sounds in

the receiver of a telephone located in a noisy room, which device is inexpensive to manufacture, easily applied to standard transmitters, and will not get out of order.

I claim as my invention:

1. A device of the character described, comprising a presser member and means for yieldingly holding said presser member against the front face of the cover plate of a telephone transmitter at a place within the margin thereof, whereby a constant pressure is exerted against said front face to eliminate the transmission of extraneous noises. 70

2. In combination with a telephone transmitter having a casing section, a front cover plate enclosing said casing section and the electrical transmitting mechanism in said casing section and a mouthpiece carried by said cover plate, a resilient presser member and means for yieldingly holding said presser member against the front face of said cover plate at a place within the margin of said cover plate, whereby a constant pressure is exerted against said front face to eliminate the transmission of extraneous noises. 80

3. A device of the character described, comprising a pair of presser members at least one of which is made of resilient material, and means for yieldingly holding said presser members against the front and rear sides of a telephone transmitter housing. 90

4. In combination with a telephone transmitter having a casing section, a front cover plate enclosing said casing section and the electrical transmitting mechanism in said casing section and a mouthpiece carried by said cover plate; a pair of resilient presser members and means for yieldingly holding one of said presser members against the rear side of said casing section and the other presser member against the front face of said cover plate at a place within the margin of said cover plate. 100

5. A device of the character described for use in connection with a telephone transmitter, comprising a spring member adapted to embrace the transmitter housing and a pair of resilient presser members carried by said spring member and urged by said spring member against opposite sides of said transmitter housing. 110

6. In combination with a telephone transmitter having a casing section, a front cover plate enclosing said casing section and the electrical transmitting mechanism in said casing section and a mouthpiece carried by said cover plate; a wire holder having a U-shaped part embracing said mouthpiece, a pair of spring loops at the ends of said U-shaped part, the other ends of said loops being extended inwardly to form legs extending along the rear side of said transmitter housing, a resilient presser member carried by said U-shaped part and urged against said front cover plate and against a side of said 120
